UNITED STATES PATENT OFFICE.

BURTON THOMPSON, OF NEW YORK, N. Y.

DESIGN FOR A BADGE.

No. 39,614.

Specification for Design.

Patented Oct. 13, 1908.

Application filed August 27, 1908. Serial No. 450,596. Term of patent 3½ years.

To all whom it may concern:

Be it known that I, BURTON THOMPSON, a citizen of the United States of America, and a resident of the city, county, and State of New York, have invented a new, original, and ornamental Design for Badges, of which the following is a specification, reference being had to the accompanying drawing, forming part thereof.

In the said drawing the figure is a front elevation of a badge showing my new design.

As shown in the drawing the badge is composed of the following letters: A, B, E, F, H, L, N, O, P, R, T, and Y. The letter A is readily found in the lower part of the emblem, while B forms the outer part of the emblem together with the central horizontal bar. E is formed by the three horizontal bars and the left end vertical bar while F is formed similarly omitting the lowest horizontal bar. H is formed by the two vertical bars and a portion of the central horizontal bar. L is formed by the left end vertical and

the lowermost horizontal bar. N is formed in the upper left hand corner of the emblem by the upper portion of the two vertical bars intersected by the upper left hand inclined bar. O is shown at the top of the emblem while P is formed by the upper portion of B and omitting the lower portion of said letter. R is formed by the upper portion of B together with the entire left hand vertical bar and the lower right hand inclined bar. T is formed by the central vertical bar and the topmost horizontal bar and Y is formed by the lower portion of the central vertical bar taken together with the two uppermost inclined bars.

I claim:

The ornamental design for a badge as shown and described.

BURTON THOMPSON.
